UNITED STATES PATENT OFFICE.

JEREMIAH M. TAYLOR, OF CROWLEY, LOUISIANA, ASSIGNOR OF ONE-HALF TO HENRY LEONARD HABETZ, OF CROWLEY, LOUISIANA.

SPOKE-TENONING MACHINE.

Application filed January 27, 1926. Serial No. 84,209.

This invention relates to new and useful improvements in wood-working machines, and particularly to machines for forming tenons on the ends of wheel spokes.

5 One object of the invention is to provide a device of this character which is simple in construction, easy in its operation, and which is readily adjustable to wheels of various sizes.

10 Another object is to provide a novel means for advancement of the cutter to the work, and for withdrawing the same therefrom.

Other objects and advantages will be apparent from the following description when 15 taken in connection with the accompanying drawings.

In the drawings:

Figure 1 is a side elevation of a tenoning machine made in accordance with the present invention.

20 Figure 2 is a top plan view of the same.

Figure 3 is a vertical transverse sectional view on the line 3—3 of Figure 2, showing the vertically adjustable block.

25 Figure 4 is a vertical sectional detail view on the line 4—4 of Figure 3.

Referring particularly to the accompanying drawings, 10 represents a table, supported on the legs 11, and having the longitudinal central slot 12 formed therein, and to which reference will be made later herein.

30 Mounted on one end of the table, at opposite sides of the slot 12, are the longitudinally extending yokes 13, the arms of which stand vertically, as clearly seen in Figure 1.

Extending transversely of the end of the table is a vertical block 14, the same being vertically slotted, at 15, and receiving bolts 16, which also pass through the adjacent

40 arms of the yokes 13. By means of these bolts 16, which are loosely disposed in the slots 15, and threaded into the arms of the yokes, the block may be adjusted to the height desired. A similar block 17, is sim-

45 ilarly mounted on the other arms of the yokes. Formed through the centers of the two blocks 14 and 17, in proper alignment, are openings 18, in which are disposed bushings 19, and through which bushings is disposed

50 the shaft 20. On the shaft 20, rearwardly of the block 14, there is mounted a crank handle 21, but this may be removed and a belt wheel substituted, when the shaft is to be driven by a motor. On the other end of

55 the shaft 20 there is mounted a chuck 22, for

receiving the tenoning tool 23. Oil cups 24 are mounted on the blocks 14 and 17 for feeding lubricant to the bushings and shaft. Fixed on the shaft 20, intermediate the blocks 14 and 17, is a circumferentially grooved collar or sleeve 25, and encircling the grooved portion of said sleeve is the eye 26 of the lever 27, said lever being pivotally supported for horizontal movement on the outstanding bracket 28, carried by the side 60 of the table. This lever is adapted to be rocked to advance or withdraw the cutter with relation to the end of a spoke. Suitable braces 29 are connected to the legs and to the sides of the table, to produce a rigid 65 structure.

Disposed transversely of the upper and lower faces of the table, and extending transversely of the slot 12, thereon, are the plates 30, and disposed vertically through the centers of these plates, and through said slot 12, is a bolt 31, the lower end of which is threaded and carries a nut adapted to be driven upwardly against the lower plate, to clamp the plates tightly against the faces 70 of the table. This permits the plates and bolt to be adjusted longitudinally of the table, toward and away from the cutter, in accordance with the length of the spokes 75 of the wheel being treated. Rotatably supported on the upper end of the bolt 31, which extends above the upper plate 30, is a cruciform member 32, the arms of which are turned upwardly, and carry screws 33 through them for biting engagement with 80 the peripheral face of the hub 34, of the wheel which is disposed on said member 32. This member is adapted to be rotated to dispose the outer ends of its spokes 35, successively in line with the cutter 23, which 85 cutter is advanced to the spoke end by means of the lever 27, the operator turning the shaft 20, by means of the crank handle, to cause the cutter to operate upon the spoke. 90

In the event that a wheel has its spokes at a higher or lower level than that at which the cutter is disposed, the blocks 14 and 17 are adjusted so that the cutter will be in proper alignment with the end of a spoke 95 of the wheel. Should the spokes be longer or shorter than usual, the plates 30 are adjusted toward or away from the block 17, so that the cutter may be more easily manipulated with relation to the spoke ends. The member 32 is adapted to be rotated so as to 100

105

110

successively dispose the spokes in position for treatment by the cutter.

What is claimed is:

5 A spoke tenoning machine including a support, a work holder on the support, yokes mounted on the support and having their arms directed upwardly, transverse blocks on the support lying against said yoke arms and having vertical slots, the yoke arms having threaded openings registering with said

slots, screws disposed through said slots and threaded into said openings for clamping the blocks in different vertical adjustments on the yoke arms, and a cutter carrying shaft rotatable through the blocks for alignment with a spoke end. 15

In testimony whereof, I affix my signature.

JEREMIAH M. TAYLOR.
